Primary Examiner — Nathan M Johnston

(57) CLAIM

The ornamental design for the U shape hair extensions holder hanger, as shown and described.

DESCRIPTION

FIG. 1 shows the front view of the U shape hair extensions holder hanger;

FIG. 2 shows the top view of the U shape hair extensions holder hanger;

FIG. 3 shows the side view of the U shape hair extensions holder hanger;

FIG. 4 shows the front environmental view of the U shape hair extensions holder hanger; and,

FIG. 5 shows the perspective view of the U shape hair extensions holder hanger.

The broken line showing of parts of the drawings is included for the purpose of illustrating use and environment and forms no part of the claimed design.

1 Claim, 3 Drawing Sheets
